(57) **CLAIM**

The ornamental design for a flask with valve, as shown and described.

DESCRIPTION

FIG. 1 is right side view showing the new design.

FIG. 2 is a left side view thereof.

FIG. 3 is front view thereof.

FIG. 4 is a back view thereof; and,

FIG. 5 is a top view thereof.

The broken lines are included for the purpose of illustrating the portions of the flask with valve that form no part of the claimed design.
